UNITED STATES PATENT OFFICE

137,981

DESIGN FOR A TOY WHISTLE

Evan Hughes, Colfax, Iowa

Application December 6, 1943, Serial No. 111,922

Term of patent 3½ years

(Cl. D34—15)

To all whom it may concern:

Be it known that I, Evan Hughes, a citizen of the United States and a resident of Colfax, in the county of Jasper and State of Iowa, have invented a new, original, and ornamental Design for a Toy Whistle, of which the following is a specification, reference being had to the accompanying drawing, forming part thereof, in which:

Fig. 1 is a front perspective view of a toy whistle showing my new design;

Fig. 2 is a rear perspective view of the same;
Fig. 3 is a bottom plan view; and
Fig. 4 is a sectional view taken on the line 4—4 of Fig. 1.

I claim:

The ornamental design for a toy whistle, substantially as shown.

EVAN HUGHES.
